BENJAMIN A. FLESHMAN AND JOHN M. KOONTZ, OF FAYETTEVILLE, WEST VIRGINIA.

RAIL-BRACE.

No. 884,917.

Specification of Letters Patent.

Patented April 14, 1908.

Application filed June 12, 1907. Serial No. 378,475.

To all whom it may concern:

Be it known that we, BENJAMIN A. FLESHMAN and JOHN M. KOONTZ, citizens of the United States, and residents of Fayetteville, 5 in the county of Fayette and State of West Virginia, have invented a new and Improved Rail-Brace, of which the following is a full, clear, and exact description.

The invention relates to railways and its 10 object is to provide a new and improved rail brace arranged to prevent spreading of the rails at curves, switches and other places, to relieve the outer rail on curves of undue strain and to subject the inner rail to a strain 15 equal to that on the outer rail, thereby dispensing with curve braces, double spiking of the outer rail and like expedients heretofore employed.

The invention consists of novel features 20 and parts and combinations of the same, which will be more fully described hereinafter and then pointed out in the claims.

A practical embodiment of the invention is represented in the accompanying drawings 25 forming a part of this specification, in which similar characters of reference indicate corresponding parts in both views.

Figure 1 is an elevation of the improvement as applied, the rails being shown in 30 cross section, and Fig. 2 is a plan view of the same.

The plates A and B of the rail brace terminate at their outer ends in integral upturned flanges A', B' engaging the outer 35 edges and top of the bases of the rails C and C', as plainly shown in the drawings, the said rail bases being engaged at the inner sides and on top by retaining flanges D, D' fulcrumed at E, E' on the plates A and B, respectively. Thus by the arrangement described the retaining flanges D and D' can be 40 readily swung into and out of engagement with the bases of the rails at the inner sides thereof, and when the retaining flanges D 45 and D' are in active position then they are fastened in place on the plates A and B by bolts F, F' or other fastening devices. The inner ends of the plates A and B terminate in threaded portions A², B² engaged by a turn 50 buckle G, to adjust the plates A and B, so as to hold the rails C and C' at the proper gage and against spreading, especially when the device is used on curves, switches and other places.

55 In order to prevent accidental turning of

the turn buckle G, a locking device is provided consisting essentially of a locking arm H fulcrumed on one of the plates (as shown, the plate A) and having an angular lug H' terminating in an eye H² adapted to receive a 60 cotter pin I, as shown in Fig. 2. After the turn buckle G is adjusted to bring the plates A and B in proper position relative to the rails C and C', then the locking arm H is swung downward into the position shown in 65 the drawings, that is, with the angular lug H' passing through the opening in the turn buckle G, and then the operator inserts the cotter pin I into the eye H², thus locking the arm H against movement and at the same 70 time preventing the turn buckle G from being turned. Now by the arrangement described the arms A and B can be quickly and conveniently adjusted, to securely hold the rails C and C' in the proper position, thus preventing 75 spreading of the rails and relieving the strain on an outer rail on curves, as the strain is equally shared by the inner rail owing to the rail brace shown and described.

In practice the rail brace is preferably 80 placed between the ties, thus allowing the use of the device without the slightest change in the road-bed or interfering with the running of the trains during the time it is placed in position.

When using the rail brace on switches and other places, slight modifications in the construction may be necessary, and hence we do not limit ourselves to the exact construction shown and described.

Having thus described our invention, we claim as new and desire to secure by Letters Patent:

1. A rail brace for connecting a pair of track rails with each other, comprising plates terminating at their outer ends in heads engaging the bases of the rails, the inner ends of the plates being threaded, a turn buckle connecting the inner threaded ends with each other, a locking arm fulcrumed on one of the said plates and having an angular flange terminating in an eye, the flange and eye being adapted to pass through the opening in the turn buckle, and a key engaging the said eye to lock the arm in place to hold the turn buckle against turning.

2. A rail brace for connecting a pair of track rails with each other, comprising plates terminating at their outer end in an upturned flange for engaging the outer edge of the base

of the rail, and a retaining flange for engaging the inner edge of the base of the rail fulcrumed to the said plate, bolts for securing the retaining flange in place on the plate, the inner ends of the plates being threaded, a turnbuckle connecting the inner ends of the plates with each other, a locking arm fulcrumed on one of the said plates and having an angular flange terminating in an eye, the flange and eye being adapted to pass through the turnbuckle, and a key engaging

the eye to lock the arm in place to hold the turnbuckle against turning.

In testimony whereof we have signed our names to this specification in the presence of 15 two subscribing witnesses.

BENJAMIN A. FLESHMAN.
JOHN M. KOONTZ.
